UNITED STATES PATENT OFFICE.

REINHARD WUSSOW, OF CHARLOTTENBURG, NEAR BERLIN, GERMANY.

METHOD FOR THE DRY COOLING OF COKE.

Application filed October 19, 1926, Serial No. 142,693, and in Germany January 17, 1923.

The present invention relates to a method of dry cooling of coke and its application to a continuously operating gas producer. The method consists in passing a neutral 5 gas or steam or a mixture of both in continuous circulation through a bed of coke to be cooled and through a saturator device with a finely divided spray of water, the gas or steam or gas and steam mixture heated 10 in the layer of coke to be cooled vaporizing a part of the water and carrying this freshly formed steam with it through the layer of coke, such excess steam with suitably high temperatures of the coke column forming 15 water gas in known manner. As a result, not only the heat content of the glowing coke is re-extracted, but the high temperature of the coke is utilized to produce a valuable product, viz—water gas.

20 In order to obtain the maximum economy, the steam is circulated only in the already preliminarily cooled part of the coke column, the excess steam produced by the hotter layers of coke being passed therethrough 25 on the contra-flow principle and thus a high grade water gas is produced in a continuous stream. This method of dry cooling of coke is preferably used in conjunction with a retort for obtaining gas from fresh coal.

30 The hot water-gas produced is led wholly or partly through the coal in contraflow and the heat required for gas making is produced by the addition of oxygen or air.

Processes according to which a cooling 35 medium circulates between a column of coke to be cooled and a heat exchange apparatus are known per se. In such processes, however, the cooling medium does not change in the course of the process and serves only 40 as a heat carrier which transfers the heat given up by the coke to a steam boiler. Under the present process the cooling medium comes into direct contact with the water to be evaporated and accordingly itself takes 45 up the steam produced, the cooling medium therefore is always newly supplemented and in dependence on the repeated production of fresh steam, the excess of steam is forced into the hotter layer of coke where in known 50 manner water-gas is formed.

It has already been proposed to employ a process of cooling and hydrating cement clinker in a cooler. For this purpose a mixture of air and steam is led through a cooler 55 which contains the cement clinker to be cooled and thence through an evaporator. In this cooler the cooling and hydrating of the clinker is effected by the mixture which, in turn, is heated. In the evaporator steam is again produced by the heated air and steam mixture by indirect transfer of heat to the water, which steam, together with the mixture, returns to the cooler. In this circulation any excess steam produced escapes 60 into the atmosphere.

The present process, however, deals with the cooling of coke by means of a gas and steam mixture with the simultaneous production of water gas. The mixture of gas and steam circulating in the cooling zone of 65 the coke column cools the coke here and, at the same time, the excess steam carried with it is forced into the hotter part of the coke column located above the cooling zone, and water gas produced in the coke column by 70 means of such steam.

One form of apparatus for dry cooling of coke and for the production of water-gas according to the present process is illustrated in Fig. 1 of the accompanying drawing. 75 Fig. 2 shows a retort for the continuous cooling of coke and the production of illuminating gas in accordance with the invention. Fig. 2' shows another form of a continuous discharging device.

In Fig. 1, *a* denotes the coke quencher in which the hot coke is introduced through the charging door *b* and is withdrawn beneath through the outlet valve *c* as the operation proceeds. *d* is a saturator with a sprinkling 80 device and *e* a pump which draws the water from the lower part of this saturator and forces it into the upper part where in known manner it trickles through the chamber after the manner of a gas washer. *f* is a fan or 85 blower which draws the steam (or, in the first stage, the air) from the lower part of the saturator in a continuous stream and forces it upwards into the already preliminarily cooled coke column. In consequence 90 of the suction action produced in the saturator by the blower *f* the steam is drawn from the lower coke cooling chamber through the pipe *g* into the saturator and thus a continuously circulating current of 95 steam is produced between the lower part of the coke charge and the saturator. This steam serves as a heat conductor since it is heated in the coke column to the desired temperature and transfers the heat taken up 100 105 110

to the water circulating in the saturator *d* and evaporates this water to an extent dependent on the transfer of heat. The water vapour thus continuously freshly produced is forced through the hot coke column above the branch *g* in contra-flow to the passage of the coke or to the temperature drop in the coke column and is here in known manner converted into water-gas. The heat of the coke in the lower preliminarily cooled part of the coke column (extending to the pipe *g*) serves thus only for the generation of steam while the heat of the upper hot column of coke is utilized to the fullest extent in the formation of water-gas by virtue of the adoption of the contra-flow principle.

In order to obtain uniform distribution of the steam being circulated over the whole cross section of the coke column the quencher is preferably enlarged at its lower end suitably at the level of the branch pipe *g* so as to form an annular channel *k* through which the steam being circulated is drawn off.

Adjacent the steam generating zone service doors *l* and horizontal supporting bars *m* are provided. On these bars may be arranged emergency bars *n* to permit of partial discharge.

With the discharge valve *c* is connected a grate *p* which moves with the valve when the latter is opened. The circulating steam is introduced between the valve *c* and the grate *p*, the grate serving to ensure that the steam will enter the coke column uniformly distributed.

A modification of this method consists in arranging the coke cooling device as a direct continuation of a continuously operated gas retort and passing the hot water-gas produced direct through the column of coal to be distilled. There is thus obtained a continuously operating retort for producing gas and also for cooling the coke produced, in which retort in a continuous operation the fresh coal is introduced above and the cooled coke withdrawn below. The whole of the conversion of heat in the operation of coal distillation and production of water-gas are thus effected directly in the retort and in a direct manner whereby several advantages result such as intensive heat exchange and improvement of the distillation product and of the coke. In order to supply the additional heat necessary for distilling the fresh coal a part of the water-gas is burned in the retort by introducing at convenient points of the retort oxygen or air in such quantity that by the combustion of the part of the water-gas the necessary additional heat requirements of the retort are met.

In Fig. 2 is illustrated diagrammatically a continuously operable distilling retort constructed to carry out this method. In this figure the reference characters *a*, *d*, *e*, *f*, *g*,

h, *k* and *o*, indicate the same parts as they do in Fig. 1. The gas making part of the retort *a*, in which the distillation of the coal as well as the production of water-gas is effected, is for that reason made considerably larger than the lower steam generating zone, *q* indicates a bunker built on the retort and made gas tight from which fresh coal passes to the retort as the other material passes through so that the column of coal is always of the same height. At the lower end of the retort is provided also a gas-tight bunker *r* in which the cooled coke is collected and from which it is discharged from time to time.

The output is regulated by providing at the lower end a feeding device consisting of feed wheels with feeding arms mounted on a shaft *s* carried in external bearings and rotated in direction of the arrow. In order to prevent the arms from moving the coke horizontally, which is dangerous and interferes with the passage of the material, there are provided between the separate feed wheels *t* protectors *u* which, as shown in the drawing, are so arranged that the coke moves downwards in a smooth path and is led to one side past the feed wheels.

In Figure 2^a, is shown another form of a continuous discharging device. In this figure *v* indicates a table-like plate arranged a short distance beneath the outlet of the retort, a reciprocating device *w* acting on the coke on this table and carrying it in its movement over the edges of the plate. Feeding may also be effected by providing the table with projections (lugs etc.) and moving it to and fro as a whole. *x* denotes a plate or the like arranged in the bunker and which, when the bunker *r* is full, is moved by the coke passing downwardly, the movement being utilized in a suitable manner for actuating an alarm device. *y* indicates the oxygen or air supply conduit referred to above, which is shown as located above the boshes *k*. The pipe *y'* represents another convenient means whereby the oxygen or air may be introduced at a different level. *z* is a regulating device, not shown in detail, for the supply of oxygen. This regulator is preferably controlled by the temperature conditions in the retort.

A further method of controlling local temperature conditions in the retort consists in introducing portions of the oxygen at different levels of the retort by means of both pipes *y* and *y'*. To avoid too considerable dilution the heating may be sub-divided into internal heating as described and a partial external heating by means of the part of the water-gas produced.

What I claim is:—

1. The method for dry cooling of hot coke and production of water gas, which comprises cooling the coke by circulating

a gaseous carrier medium, chemically inert with respect to the coke, through the lower portion only of a vertical column of the coke, the upper portion of the column being
5 at a temperature sufficient to carry out the water gas reaction; injecting into the circulating gaseous medium, while out of contact with the coke, a spray of water to cool said medium and to produce steam; allowing
10 gas to pass through the column from the lower portion of the column to the top there-

of; and withdrawing at the top of the column the water gas formed by the reaction of the steam with the hot coke.

2. In combination with the method set forth in claim 1, the additional feature of continuously introducing hot coke to the top of the column and discharging cool coke from the bottom of the column.

In testimony whereof I have signed my name to this specification.

REINHARD WUSSOW.
